(57) **CLAIM**

The ornamental design for a linear ceiling channel, as shown and described.

DESCRIPTION

FIG. 1 is a perspective view of a linear ceiling channel showing our new design;

FIG. 2 is a side view thereof;

FIG. 3 is a bottom view thereof;

FIG. 4 is an end view thereof;

FIG. 5 is an enlarged view thereof taken from portion 5 of FIG. 3; and,

FIG. 6 is a cross-sectional view thereof, taken along line 6-6 of FIG. 5.

The dot-dash broken lines of FIG. 3 are included to show a partially enlarged view only and form no part of the claimed design.

The linear ceiling channel is shown with a symbolic break in its length. The appearance of any portion of the linear ceiling channel between the break lines forms no part of the claimed design.
